G. PARKER

ELECTRIC CIGAR LIGHTER

Filed April 8, 1926

INVENTOR
George Parker
BY
H. G. Manning
ATTORNEY

UNITED STATES PATENT OFFICE.

GEORGE PARKER, OF MERIDEN, CONNECTICUT.

ELECTRIC CIGAR LIGHTER.

Application filed April 8, 1926. Serial No. 100,561.

This invention relates to ignition devices, and more particularly to a cigar lighter adapted to be detachably connected to a standard electric lamp socket.

5 One object of this invention is to provide a device of this nature which will be simple in construction, inexpensive to manufacture, easy to install and manipulate, compact, ornamental in appearance, and very efficient 10 and durable in use.

With these and other objects in view there has been illustrated on the accompanying drawings one form in which the invention may be conveniently embodied in practice.

15 Fig. 1 represents a side view of the cigar lighter together with the cord and plug for connecting it to an electric lamp socket.

Fig. 2 is a side sectional view of the cigar lighter as it appears when the ignition plug 20 has been removed.

Fig. 3 is a longitudinal sectional view of the ignition plug itself.

Fig. 4 is a top view of the ignition plug, the cover being shown partly broken away 25 to show the arrangement of the ignition coil beneath it.

Referring now to the drawings in which like reference numerals denote corresponding parts throughout the several views, the 30 numeral 10 indicates a hollow standard or base adapted to rest upon a table or other support. The base 10 is provided at its bottom with a horizontal flange 11 having an aperture 12 for receiving a two-wire electric conductor cord 13, said cord 13 being 35 connected at one end to a lamp socket plug 14 of any standard form.

The base 10 is formed at its top with a vertical tapered tubular section 15, said section being adapted to receive the body member to be hereinafter described. The section 15 near its bottom has an internal flange 16 which forms a seat for a vertical insulating strip 17 upon which are mounted the movable and stationary contacts of the operating switch to be described later.

In order to support the ignition plug on an axis slightly inclined from the horizontal and in a convenient position for the smoker, 50 provision is made of a cup-shaped body member 18 supported upon the tubular section 15, said body member having a depending flared section 19. An annular shoulder 20 is formed below said flared section 19, and said shoulder 20 is adapted to seat upon 55 the top of the upper tubular section 15 of

the base 10. Below the shoulder 20, a neck 21 is provided, said neck 21 having a pair of oppositely arranged slots 21^a which serve to hold the strip 17 against rotation. The 60 neck 21 may be locked in position upon said base in any suitable manner but preferably by a set screw 22, as clearly shown in Fig. 2.

The open end of the body member 18 is provided with a detachable mouth piece 23 65 which is outwardly flared at 24 to facilitate the insertion and removal of an ignition plug 25. The mouth piece 23 is held in place upon the end of the body member 18 by a friction fit. The body member 18 has an 70 annular rib 25^a adjacent its open end to limit the inward movement of said mouth piece.

In order to detachably hold the ignition plug 25 in the open end of the body member 18, a cylindrical screw shell 26 is provided, said screw shell being separated from said body member by an insulating band 27, as shown in Fig. 2. The rear of the screw shell is open so as to permit the center contact of the ignition plug 25 to engage a resilient looped end 28 of a contact strip 29, said strip being secured at its inner end to a horizontal insulating strip 30. The strip 30 is held rigidly within the center of the 80 body member 18 by a small angular metal bracket 31 joined as by soldering to the rear part of the screw shell 26. The inner end of the insulating strip 30 is seated within a conical depression 32 in the closed end 90 of the body member 18.

As clearly shown in Fig. 2, the conductor cord 13 contains two insulated wires 33 and 34, the wire 33 being connected at 35 as by soldering to the contact strip 29, while the wire 34 is connected at 36 as by soldering to the lower part of a resilient movable contact 37 of the controlling switch. The lower end of the movable contact 37 is bent rearwardly and upwardly and then passed 100 forwardly through an aperture 38 in the vertical insulating strip 17. The upper free end of the movable contact 37 is adapted to be constantly engaged by a push button 39, said button having on its rear side a flange 105 40 which serves to retain said push button in its aperture 41.

Located in alignment with the free upper end of the movable contact 37 is a U-shaped stationary metallic contact clip 42, said clip 110 having its rear ends 42^a passed through a pair of apertures in the vertical insulating

strip 17, said ends 42^a being bent parallel to said strip for holding the clip rigidly in position.

In order to electrically connect the stationary contact 42 with the screw shell 26, an insulated wire 43 is provided, said wire 43 having its terminals joined as by soldering to the clip 42 and shell 26, respectively.

The ignition plug 25 comprises an outer tube 44 of porcelain or other suitable insulating material, said tube 44 having a reduced tapering rear section 45 within which is mounted a metallic eyelet member 46, the ends of said eyelet member being headed over upon the base 47 and an interior shoulder 48, respectively, of said plug. The outer end of the tube 44 is enlarged to provide an interior seat 49 for an insulating disc 50 upon which the heating coil 51 of resistance wire is adapted to be wound. The disc 50 is provided on its top and bottom faces with a plurality of parallel guiding ribs 52 and 53, the outer ribs 52 being staggered with respect to the inner ribs 53. The disc 50 is also provided with a pair of oppositely disposed apertures 54 and 55. By means of this construction, after the coil 51 has been wound around said disc 50 in the grooves between the ribs 52 and 53, the extremities 56 and 57 of said coil may be passed through said apertures 54 and 55. The extremity 56 may then be clamped between the eyelet member 46 and tube 44. The other extremity 57 of the coil 51 will then be passed through the aperture 55 in the disc 50, and an opening 58 in the outer tube 44 and will be clamped securely against said outer tube 44 by a screw shell 59 which forms the outer contact of said plug.

The top of the ignition plug is protected by a cover ring or cap 60, said cap serving to hold a perforated disc 61 of mica or other durable heat resisting material, whereby the heating coil 51 will be prevented from contact with exterior objects. It will be understood that in use the heat radiated through the perforations of the disc 61 will be sufficient to ignite a cigar or cigarette.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In an electric cigar lighter, a tubular vertical standard open at its top, means in said standard for supporting the base of a vertical insulating strip, a horizontal body member having a depending neck seated within the open top of said vertical standard, an ignition unit in said body member, said neck having slots to fit over and lock said insulating strip, a switch supported by said strip and connecting the ignition unit with a source of current, and means for operating said switch.

In testimony whereof, I have affixed my signature to this specification.

GEORGE PARKER.
